UNITED STATES PATENT OFFICE.

CHARLES W. SMITH, OF NORWALK, OHIO.

DESIGN FOR A CURTAIN-POLE BRACKET.

SPECIFICATION forming part of Design No. 24,105, dated March 12, 1895.

Application filed February 9, 1895. Serial No. 537,830. Term of patent 7 years.

To all whom it may concern:

Be it known that I, CHARLES W. SMITH, a citizen of the United States, residing at Norwalk, in the county of Huron and State of Ohio, have invented a certain new and useful Design for Curtain-Pole Brackets; and I do declare the following to be a full, clear, and exact description of the invention, such as will enable others skilled in the art to which it appertains to make and use the same, reference being had to the accompanying drawing, and to the letters of reference marked thereon, which forms a part of this specification.

15 The figure is a side elevation of my design for a curtain pole bracket.

My design has reference to brackets for curtain poles, and the special features of the design being an annular curtain pole supporting portion A, the said ring being circular in cross section having the cylindrical portion B and the spherical or globular member C interposed between the said annular portion and the semi-cylindrical wall engaging portion D forming a support for the portion A, the semi circular portion E provided with

beads e near its free ends, the ends concaved and tapering to rounded points F, the said semi-circular member having contact with the annular portion and the semi-cylindrical portion D, at the points G. The wall engaging portion D has a flat side D' and K is a bead convex in shape and J, J, are concaved recesses flaring outwardly on each side of said bead, and near each end of the semi cylindrical portion D, are the contracted or concaved surfaces L, L, flaring toward the middle of the semi cylindrical portion D, the tapering ends terminating in a semi-spherical portion R at each end, each of which is provided with a semi cylindrical portion S integral with the semi conical portion T.

35 What I claim is—

The design for a curtain pole bracket as herein shown and described.

40 In testimony whereof I affix my signature in presence of two witnesses.

CHARLES W. SMITH.
